UNITED STATES PATENT OFFICE

SIDNEY G. DOWN, OF EDGEWOOD, PENNSYLVANIA, ASSIGNOR TO THE WESTINGHOUSE AIR BRAKE COMPANY, OF WILMERDING, PENNSYLVANIA, A CORPORATION OF PENNSYLVANIA

MAGNETIC BRAKE DEVICE

Application filed September 22, 1927. Serial No. 221,166.

This invention relates to the type of railway brake, in which a magnetic brake shoe is normally held suspended away from the rail, and is adapted upon energization to be 5 attracted to the rail and thereby act as a brake.

In order to apply the brakes, the magnetic pull exerted by the brake shoe magnet must be sufficient to cause movement of the brake 10 shoe through the gap or clearance space normally existing between the shoe and the rail. As the shoe approaches the rail, the magnetic attraction increases and the result in that the shoe engages the rail suddenly and causes a 15 grabbing effect, this effect being more pronounced as the gap or clearance space is increased due to wear of the brake shoe and the like.

In order to obviate the above action, the 20 principal object of my invention is to provide means for moving the brake shoe to and from the rail, which means is adapted to operate independently of the magnetic pull of the brake shoe.

25 In the accompanying drawing, the single figure is a diagrammatic sectional view of a magnetic brake apparatus, embodying my invention.

As shown in the drawing, the apparatus 30 may comprise a magnetic brake shoe 1, having a magnet coil 2 and being suspended over the rail 3 by means of a rod 4. The piston 5 is secured to the upper end of the rod 4 and said piston is contained in a cylinder 6, which 35 is suitably mounted on the vehicle.

A coil spring 7 is disposed in the chamber 8 and acts on the piston 5, so as to normally maintain the brake shoe 1 in its suspended position. Also mounted on the vehicle is a 40 valve device comprising a casing 9, containing a valve piston 10. Said valve piston is provided with a seat adapted to engage an annular seat rib 11, and a pipe 12 opens to the 45 space within the seat rib, said pipe being either connected to the straight air pipe of a fluid pressure brake system, or to the usual brake cylinder 28.

The valve piston 10 is urged to its seat by 50 a coil spring 13 and the chamber 14 at the

spring side of the valve piston is connected to an atmospheric port 15.

The chamber 16 outside of the seat rib 11 is connected to a pipe 17 which leads to piston chamber 18, and a vent passage 19 connects chamber 16 with chamber 14, when the valve piston 10 is seated. 55

A switch device for controlling the circuit of the brake shoe magnet 2 is also provided, comprising a casing 20 containing a valve 60 piston 21 adapted to seat on a seat rib 22, the space within the seat rib being connected to pipe 17.

A coil spring 23 urges the valve piston 21 to its seat and said piston is provided with a 65 stem 24 carrying at its outer end a switch contact 25, adapted when moved upwardly from the position shown in the drawing to connect contacts 26 and 27 for closing a circuit from a source of current through the 70 magnet coil 2.

In operation, when the operator initiates an application of the fluid pressure brakes, fluid under pressure is supplied to pipe 12, either from the brake cylinder or from the 75 straight air brake pipe.

The valve piston 10 is unseated by pressure of fluid supplied through pipe 12 to the space within the seat rib 11 and when unseated, the full area of the piston being exposed, the valve piston is quickly moved to its outer position. 80

Fluid under pressure is then supplied from chamber 16 through pipe 17 to piston chamber 18 and the piston 5 is thereupon actuated 85 so as to move the brake shoe 1 into engagement with the rail 3 and cause a braking effect on the vehicle by the frictional engagement of the shoe with the rail.

Owing to the restricted area of the switch 90 piston 21 which is open to the pressure in pipe 17 when the piston is seated, and the resistance of the spring 23, the piston 21 will not move until the piston 5 has been shifted to cause the brake shoe to engage the rail. 95

The pressure of fluid from pipe 17 then increases sufficiently to cause the piston to move away from the seat rib 22 and the full area of the piston 21 being then exposed to the fluid pressure supplied through pipe 17, the piston 100

is quickly shifted to its outer position, in which a circuit is closed from a source of current through the magnet coil 2. The magnetic brake shoe is thus energized so that the 5 brake shoe is pressed against the rail with a force corresponding with the current flow through the magnet coil 2.

When fluid under pressure is released from pipe 12 in releasing the brakes, the fluid pressure below the valve piston 10 is also reduced 10 and when reduced to a predetermined degree, the valve piston 10 is moved back to engage the seat rib 11 by the spring 13. The reduction in pressure in pipe 17 first causes the 15 movement of piston 21, since the magnetic pull of the brake shoe 1 resists the upward movement of piston 5. The downward movement of piston 21 causes the switch contact 25 to move so as to open the circuit of the magnet coil 2 and the magnet coil being thus de- 20 energized, the piston 5 is moved upwardly by the spring 7. Fluid under pressure remaining in the pipe 17 after the valve piston 10 moves to its seat is vented through passage 25 19 to the atmospheric port 15.

While one illustrative embodiment of the invention has been described in detail, it is not my intention to limit its scope to that embodiment or otherwise than by the terms of 30 the appended claims.

Having now described my invention, what I claim as new and desire to secure by Letters Patent, is:—

1. In a vehicle brake, the combination with 35 a magnetic brake shoe normally held out of engagement with a friction surface, of means for moving the shoe to the friction surface while the shoe remains deenergized and for then energizing said shoe.
2. In a vehicle brake, the combination with 40 a magnetic brake shoe normally held out of engagement with a friction surface, of means operated by fluid under pressure for moving the shoe to the friction surface and means operated by fluid under pressure for then closing a circuit for magnetizing said shoe.

In testimony whereof I have hereunto set my hand.

SIDNEY G. DOWN.
